ADJUSTABLE STABILIZER FOR TRAILERS, CAMPERS AND THE LIKE

Herbert A. Grosz, Rte. 1, Box 1557,
Elk Grove, Calif. 95624

Filed Oct. 9, 1968, Ser. No. 13,906

Term of patent 14 years

Int. Cl. D17—05

U.S. Cl. D41—1

FIGURE 1 is a front perspective view of an adjustable stabilizer for trailers, campers and the like showing my new design;

I claim:

The ornamental design for an adjustable stabilizer for trailers, campers and the like, as shown and described.
